NECKTIE RACK

Richard H. Arbib, New York, N. Y., assignor to
Swank, Inc., a corporation of Delaware

Application March 17, 1950, Serial No. 150,115

3 Claims. (Cl. 211-)

This invention relates to a neck tie rack for holding neck ties, more particularly the four-in-hand type of necktie.

One of the objects of this invention is to provide a neck tie rack in which individual ties may be individually mounted, and moved about the rack.

Another object of the invention is to provide a plurality of members for individually receiving the ties each of which may be members made of a single piece material, such for instance as a non-metallic material.

Another object of the invention is to provide an individual mounting member for each necktie.

Another object of the invention is to provide a member for each of the ties which member may be of a color corresponding generally to the color of the tie.

Another object of the invention is to provide members which may be relatively moved for easier selection of the neck tie desired from the rack.

Another object of the invention is to provide the rack with a wall mounting means so that the rack itself may be moved with reference to its mounting means upon the wall.

Another object of the invention is to cover screws or bolts which are used as a mounting means by some ornamental cover.

Another object of the invention is to suspend the tie from the rack and yet prevent the member from swinging or oscillating with reference to the rack.

With these and other objects in view the invention consists of certain novel features of construction as will be more fully described and particularly pointed out in the appended claims.

Figure 1 is a perspective view of a neck tie rack in accordance with this invention showing fragmentally a wall for mounting the same.

Figure 2 is a sectional view of the rack, shown in Figure 1.

Figure 3 is a sectional view substantially along line 3-3 of Figure 2 with the rack mounting means in section.

Figure 4 is a sectional view showing one of the members as twisted for removal from the rack.

Figure 5 is a perspective view of a rack of a somewhat modified construction.

In proceeding with this invention, I provide a frame usually of metal and generally in the form

2
of a circle or loop and through some means which will permit sliding of the frame therethrough this frame is mounted upon a wall. Some non-metallic means cut out from sheet stock may be slotted so as to provide a horizontal bar to receive a tie and some other means may be formed for inter-engagement with the rack in such a manner that the member may slide along the rack.

10 With reference to the drawings, 10 designates a loop or frame of hollow construction which in cross section is elliptical or oblong, as shown in section at 11 in Figure 2. This frame is slotted as at 12 on its lower face and is mounted in a bracket 13. This bracket comprises a plate 14 with openings 15 therethrough for the reception of screws or bolts to attach it to a wall 16. Arms 17 extend outwardly from the plate 14 for the reception of the frame 10. These arms are bent inwardly, as at 18, about the frame to provide a shape to closely fit the frame although of such cross section that the frame may be slid through the arms for adjustment of its position.

A sheet metal cover 19, having a top wall and sidewalls 20 corresponding to the peripheral shape of the bracket 14, will snap into engagement with lips 21 on the bracket so as to hold this cover in place. The side walls 20 of the cover will be notched as at 22 so as to permit the frame to be slid therethrough.

30 The neck tie mounting member, as shown in Figures 1 to 4, designated 25, comprises a non-metallic sheet of material having a body portion 26 which is cut away as at 27 to provide a horizontal bar 28 with an opening 29 from the outer edge so that a neck tie may be positioned through this opening and draped over the bar 28. The general configuration of this member 25 is triangular with a portion 30 extending from the upper apex of the triangle and of a size to loosely fit between the edges of the slot 12. A T-shaped head 31 is provided at the upper end of the neck so as to extend over the wall at either side of the slot 12 and suspend this member with a tie thereon in position. In order to remove the member, either with or without the tie thereon, the member is turned from the position shown in Figure 2 to the position shown in Figure 4. The member being of a thickness less than the slot 12 permits of it being withdrawn from the slot.

Any number of these members may be provided and by being made of some of the synthetic resins, such as the poly-vinyl chlorides or methyl methacrylate (Lucite) may be of any color desired.

In some cases instead of providing a member such as 25, a different form of member, designated 35, shown in Figures 5 and 6 is provided. In this frame the frame 33 has an elliptical section with its major axis vertical, as shown at 34, in Figure 6. The member 35 is cut away with the opening 36 to provide a horizontal bar 37 over which the neck tie 38 is draped. A notch 39 provides access to the bar for positioning the neck tie thereon. This member 35 is also generally triangular, but instead of the T-shaped head and neck, as shown in Figures 1 and 2, the member 35 is further cut away to provide a slot 40 which is of the size and shape of generally the elliptical form of the rack 33, so that the rack may nicely fit this space 40 and prevent rotation of the member about the frame, although sliding of the member along the frame is provided for. However, the member may be removed from the frame, as shown in Figure 6, by spreading the opening 39 which is permitted by the material being resilient.

I claim:

1. A necktie rack comprising a bracket, a hollow frame having a slot in its lower edge and mounted in a horizontal position in said bracket, a plurality of flat members of a thickness less than the width of said slot, each of said members having a bar adapted to support a necktie and

each having a neck extending through the slot with a head extending over the material of said frame on either side of said slot to support the member therein but permitting turning about said neck for detachment through said slot.

2. A necktie rack as in claim 1 wherein said frame is slidably mounted in spaced arms on said bracket.

3. A necktie rack as in claim 1 wherein said frame is metal and said members are non-metallic.

RICHARD H. ARBIB.
